ABSTRACT OF THE DISCLOSURE

A method and apparatus for forming a ring structure comprised of a multiple number of elements substantially forming the ring, which sections are utilized in cathode ray guns to provide the electrical circuit for energizing the cathode filaments of the electron gun. Four separate sections form the ring. The method and apparatus for forming the arrangement is to provide a single damp member having the thickness of the order of 5 mils and mounting the member upon a jake to form a substantially circular shaped configuration. The member is then positioned in close proximity to the electron gun structure adjacent the elements to which it is being mechanically connected. The ring shaped member is then welded to the supporting structures and, after weldment, is positioned in a ring cutter assembly which cuts the substantially ring shaped member at three points located approximately 120° apart to thereby form four separate elements which are then utilized for electrical connection to filament leads of a plurality of cathode heaters mounted within the electron gun structure. This technique replaces the conventional technique in which six separate elements are utilized to form the filament ring.

The present invention relates to electron tube fabrication and more particularly to a novel method and apparatus for fabricating cathode ray tube electron guns especially of the type employed in color TV tubes wherein the six separate elements heretofore utilized to form the filament ring are replaced by a single element which is then welded and cut at predetermined locations to form the filament ring.

In order to mass produce electron tubes of the type having a multiplicity of components it becomes necessary to both automate as many operations in electron tube fabrication as is possible, as well as striving to reduce the number of total operations required in the fabrication of electron tubes.

As one example, in the mass production of electron gun assemblies utilized in color TV receiver tubes, the number of components comprising the electron gun is large and hence the number of fabrication steps is quite large, necessitating automation and a reduction in the number of fabricating steps to the greatest practical extent.

Electron gun structures utilized in color TV receiver tubes of the shadow-mask type are each comprised of three separate electron guns arranged substantially at 120° intervals about a central axis in order to produce the three separate electron beams which are scanned across the tube shadow-mask to pass through the openings in the shadow-mask and to impinge upon the associated colors of the phosphor dot pattern and thereby reproduce the original color image. The filaments of the individual electron guns within the composite structure are connected in electrical circuit by means of a filament ring comprised of a number of separate components sufficient to electrically couple all of the filament leads as well as to provide two tabs for electrical connection to

2

the filament power supply. Conventional methods for fabricating the filament ring consisted of providing the total number of individual segments, positioning these segments relative to the filament leads, welding the components to associated supporting structures and then welding these elements to associated leads of the filaments. Components which serve to provide the filament power are typically arranged in a ring-shaped fashion and are commonly referred to as collectively forming the filament ring structure. Due to the rather small size and fragile nature of these components, handling and welding becomes rather complex and tedious.

The present invention is characterized by providing novel apparatus for fabricating the filament ring structure in which only a single part is utilized to form the composite ring structure, which single member is appropriately welded to the supporting structure and then simultaneously cut in a plurality of locations and by a single cutting operation to form the separate segments or sections of the filament ring preparatory to the welding of the separate sections to the cathode heater filament leads.

The present invention is comprised of a heater ring fixture for receiving and positioning, in arcuate form, a single stamped member. The fixture which is formed of a metal having good conductive properties is placed in a welding fixture so as to operate as a first electrode of the welding apparatus. The remaining structure of the electron gun is lightly force-fitted to one end of the fixture so as to be aligned with the single stamped member. The welding unit includes a second welding electrode and means for positioning the second electrode relative to points between the stamped member and the related supporting components of the electron gun structure and then producing each weld. Upon completion of the welding operation, the stamped member is simultaneously cut at predetermined intervals around its periphery to form the final filament heater ring which is then ready to be joined to the individual filaments. This method and apparatus thereby enables the filament heater ring to be fabricated rapidly and accurately through mass production techniques, wherein the operations are performed substantially automatically and the number of fabrication steps are substantially reduced.

It is therefore one object of the present invention to provide a novel method and apparatus for forming the heated ring assembly of electron gun structures in a rapid, reliable and substantially automatic fashion.

Another object of the present invention is to provide a novel fixture and ring cutter and machine for forming a heater ring assembly wherein the fixture is designed to hold a single stamping member, to operate as an electrode for the welding operation and wherein the ring cutting machine simultaneously cuts the stamping into three separate components preparatory to establishing the electrical circuit path for the heater filament leads such that the above fabrication steps are performed rapidly and accurately as compared with the conventional techniques.

These as well as other objects of the present invention will become apparent when reading the accompanying description and drawings in which:

FIG. 1 is a plan view showing the stamped part utilized with the method and apparatus of the present invention.

FIGS. 2a and 2b are side and end views respectively of the heater ring fixture utilized for mounting the stamping shown in FIG. 1.

FIGS. 3a and 3b are elevational and top views respectively, showing an electron gun structure fabricated in accordance with the principles of the present invention

FIG. 4 is a plan view showing a welding apparatus

which may be utilized with the apparatus of the present invention.

FIGS. 5a and 5b are end views, respectively, showing the cutting apparatus of the present invention.

FIGS. 6a, 6b and 6c show further details of the apparatus of FIGS. 5a and 5b, wherein FIG. 6a is a sectional view taken along the lines A-A' of FIG. 6a and wherein FIG. 6c is a sectional view taken along the lines B-B' of FIG. 6a.

Referring now to the drawings, FIG. 1 shows a plan view of a stamping utilized with the method and apparatus of the present invention in which stamping 10 is a flat metallic member which may preferably be stainless steel, whose planar dimensions are preferably as shown in the figure and whose thickness is of the order of 0.005 inch. As can clearly be seen from this figure, the stamped member is a substantially flat thin metallic member and has a C-shape configuration comprised of a central portion 11 and upwardly projecting arms 12 and 13 which form tabs for connecting an electrical circuit thereto in a manner to be more fully described.

FIG. 3a shows an elevational view of a portion of an electron gun assembly and FIG. 3b shows the top view of the electron gun assembly of FIG. 3a which may be fabricated in accordance with the concepts of the present invention. The electron gun assembly 20 is comprised of three separate electron gun portions 21-23 which are arranged at 120° intervals about a central axis designated by the point 24 in FIG. 3b. Since all of the electron gun structures are substantially identical to one another, only one of these structures will be described herein for purposes of simplicity. The electron gun 22 is comprised of a cathode member 25 welded within a supporting cylinder 26. The cathode is heated to a temperature sufficient to cause the cathode to emit electrons with the electron emission toward the face of the cathode ray tube being controlled by a control grid 27. The cathode 25 is heated by a filament positioned within the hollow interior 25a of cathode 25 and is a thin wire which heats the cathode to an elevated temperature level sufficient to cause the cathode to emit electrons. The filament is provided with a pair of leads 128 extending out of the opening 25a of the cathode, which leads are then electrically connected to a pair of conductive sections 29 and 30. The filament leads of electron gun 21 are similarly electrically connected to conductive members 29 and 31, while the filament leads of electron gun 23 are electrically connected to conductive members 30 and 32, respectively, to form a series circuit simultaneously energizing all of the filaments of the three electron guns 21-23. The electrical circuit is established through a pair of tabs integrally formed with and extending upwardly from conductive pieces 31 and 32, which tabs are designated by the numerals 33 and 34, respectively.

The electron gun structure is further provided with three elongated insulating members 35-37 which mechanically support all components of the electron gun structure while electrically insulating all of the parts. These insulating members, such as, for example, member 35 are provided with a pair of metallic support members 38 and 39 whose first ends are imbedded into the insulating member 35 and whose free ends are bent outwardly to form welding surfaces for the support of conductive member 29. Insulating members 36 and 37 are likewise provided with supports for respectively welding conductive segments 30, and 31-32 thereto. It can clearly be seen from a consideration of FIG. 3b that the conductive members 29-32 form a circular or ring-shaped configuration and hence are referred to as the cathode heater ring assembly.

Heretofore the separate segments 29-32 were individually cut to size and formed so as to have an arcuate shape, after which these separate sections were then welded to the associated supports. The present invention provides a method and apparatus for forming the cathode heater ring assembly from a single stamped member of the type shown in FIG. 1, which single member is then bent

to form the circular configuration welded to the aforementioned supports and then cut at the gaps 40, 41 and 42 between the separate sections so as to automate the fabrication of the cathode heater ring assembly and to eliminate a number of fabrication steps and thereby simplify the manufacture of electron gun structures of the type shown in FIGS. 3a and 3b.

FIGS. 2a and 2b are top and side views, respectively, of a ring fixture 15 utilized to form and weld the flat stamped member 10 of FIG. 1 to the electron gun structure.

The ring fixture 15 is formed of a conductive metallic material and is comprised of a first cylindrical shaped member 16 having a central opening 16a. A second circular shaped member 17 formed of a conductive metallic material has its left-hand end (relative to FIG. 2b) inserted into the right-hand end of opening 16a. These members are rigidly joined to one another by suitable fastening means (not shown) threadedly engaging tapped apertures 18a-18c and having their forward ends bearing against the surface of member 17 to rigidly secure member 17 within member 16.

Metallic member 17 is provided with a circular shaped flange 17a having two slots 17b and 17c.

The stamped member 10 (see also FIG. 1) is placed around the periphery of member 17 near its right-hand end so that the tabs 12 and 13 pass through slots 17b and 17c and extend into a groove 16b formed between flange 17a and a continuous shoulder 16c formed in member 16. A closed loop garter spring (shown only in sectional fashion in FIG. 2b) is fitted around groove 16b so as to bear upon tabs 12 and 13 and maintain the stamped member 10 in the curved position about member 17 as shown best in FIG. 2b. This fixture is then placed upon a welding apparatus 50, shown in FIG. 4. The welding apparatus 50 is comprised of a motor 51 or any other suitable driving means for the purpose of rotating a shaft 52 mechanically coupled thereto. The opening 16a of fixture 15 is force fitted upon the end of shaft 52 in the manner shown in FIG. 4. The electron gun structure 20 (minus the cathode heater ring) is force fitted upon the right-hand end of fixture 15 so that its support members (see support members 38 and 39, for example, of FIG. 3b) embrace the stamped member 10 such that the support members make physical engagement with the stamped member at spaced intervals around its surface. A pin 19 fitted into an opening 17d in fixture member 17 further acts to centrally locate and orient the electron gun structure 20 relative to fixture 15. The pin is positioned in the open space between the electron gun structures and is substantially aligned with the longitudinal axis of the gun structure as represented by the point 24 of FIG. 3b. Pin 19 orients the location of the ring tabs with respect to each of the electron gun barrels, i.e., the red, green or blue gun.

The fixture 15 is electrically coupled by any suitable means to an energy source 53. The electrical coupling may be by means of a lead 54 which may be electrically connected either to fixture 15 or shaft 52. If desired, lead 54 may make sliding electrical connection with either shaft 52 or fixture 15. An insulating coupled 55 may electrically insulate motor source 51 from fixture 15 while mechanically coupling the output of motor 51 to the fixture. The fixture 15 serves as one electrode of the welding apparatus. The other electrode is coupled by lead 56 to a second electrode 57 positioned along one radius of the fixture and having its tip immediately adjacent the outer periphery of the electron gun support members (such as support members 38 and 39, for example).

The welding operation is performed in the following manner:

Motor means 51 is energized to rotate fixture 15 in order to position the points to be welded immediately beneath the tip of electrode 57. For example, considering FIG. 3b, the first weld may occur at point 58 for the purpose of joining support 39 to segment 29. Obviously, the

starting point may occur anywhere around the periphery of the electron gun structure and point 58 is merely cited as being one exemplary starting point. Motor means 51 is deenergized to hold this position and energy source 53 is energized to provide a weld at point 58. Motor means 51 is then energized rotating fixture 15 so as to locate point 59 (see FIG. 3b) immediately adjacent the tip of electrode 57. Motor means 51 is then deenergized and energy source 53 is energized to produce a weld at point 59. Before rotation of fixture 15, electrode 57 is retracted by either mechanical or automatic means so as to move the electrode in the direction shown by arrow 60 to provide sufficient clearance for support member 36 upon rotation of fixture 15. Motor means 51 is then energized to place point 61 immediately beneath the tip of electrode 57. Electrode 57 is then moved either by mechanical or manual means in the direction shown by arrow 62 so as to have its tip immediately adjacent point 61. Energy source 53 is then energized to produce a weld at point 61. The fixture 15 is repeatedly rotated and electrode 57 is further retracted when necessary to provide welds at the points 63, 64 and 65 so as to weld the stamped member at spaced intervals around its surface to associated supports of the electron gun structure.

Upon completion of the welding operation, the electron gun structure may simply be removed from fixture 15 and placed in a cutting assembly to form the separate segments 29, 30, 31 and 32 by means of a cutting assembly shown in FIGS. 5a-6c.

Cutting assembly 70 is comprised of a support or base member 71 which may be placed on any suitable support surface. A cutter base 72 is mounted upon the plate 71 by means of three stands off 73a-73c whose bottom ends are secured by fastening means 75 (only one of which is shown in FIG. 5b for purposes of simplicity), and whose top ends are secured to cutter base 72 by fastening means 76a-76c, respectively. Cutter base 72 is provided with a central opening 72a surrounded by an upwardly extending flange portion 72b integrally formed with space 72. A cylindrical shaped mandrel 73 is positioned within opening 72a and has its lower end 73a (of slightly smaller diameter) force fitted into a cooperating opening 74a provided in mandrel locating block 75 secured to base 72 by fastening means 76. Mandrel 74 is provided with a circular groove 74b near its upper end and with three slots 74c-74e arranged at 120° intervals about the top end of the mandrel.

A ring shaped member 77 is secured to base 72 and is provided with an opening 77a which surrounds and is spaced from flange 72b. Member 77 is provided with a flat circular shaped surface 77b for slidably supporting a cam ring 78 which may be rotated in opposing directions as shown by double headed arrow 79 by an operating mechanism to be more fully described.

The operating mechanism is comprised of an air cylinder apparatus 79 having a first end thereof secured to support member 71 by fastening means 80. While not shown in detail for purposes of simplicity, it should be understood that the air cylinder assembly 79 is provided with a hollow cylindrical shaped interior for reciprocally mounting and moving a piston member mechanically coupled to a connecting rod 81. The forward end of the connecting rod is provided with an eyelet 82 for receiving a fastening member 83 which threadedly engages a tapped aperture 78a provided in cam ring provided in cam ring 78. In operation air pressure is introduced into the cylinder (by means not shown) causing connecting rod 81 to move toward the right (relative to FIG. 5a) to rotate cam ring 78 in a counterclockwise direction relative to FIG. 5a. Removal of the air pressure and application of a vacuum or alternatively application of air pressure in the opposite surface of the piston serves to move connecting rod 81 toward the left relative to FIG. 5a causing the cam ring 78 to rotate in the clockwise direction relative to FIG. 5a.

Cam ring 78 is provided with three elongated cam slots 79a-79c arranged at substantially equally spaced intervals about the cam ring. Each of these slots receive a cam follower 82-84 respectively, which are arranged to slidably engage the peripheries of their associated slots. Since each of the cam followers are substantially identical in configuration and function, only one will be described herein for purposes of simplicity. Considering FIG. 6b, the cam follower 84 slidably engaging slot 80 is comprised of a circular shaped roller member 83a mechanically coupled to a pin 83b extending into a suitable opening provided in member 77. Pin 83b is secured within the opening in member 77 by means of a set screw 85 fitted into a tapped aperture 77c so as to secure pin 83b to member 77. Roller 83a is secured to pin 83b so as to prevent any linear motion between the two parts, thereby preventing roller 83 from lifting upwardly and away from pin 83b. However, roller 83a is free to rotate about pin 83b. Each of the blocks 77, 88 and 89 (see FIGS. 6a and 6c) is provided with a pair of shoulders such as for example, the shoulders 77d and 77e arranged to slide within an elongated slot 90a provided within a cover plate 90. Similar slots are provided for each of the members 88 and 89. Circular cover plate 90 may be secured to cutter base 72 in any suitable manner such as by elongated fastening means, for example, which may be positioned at spaced intervals between the slides 77, 88 and 89. The slide 77 is provided with a narrow elongated slot 77d fitted with a cutter member 91 shown best in FIG. 6b. Three such cutter members 91-93 are provided for each of the slides 77, 88 and 89, respectively. Each cover plate is fitted with a slide cover such as, for example, the cover 94 secured to the top of the slide 88 by fastening means 95. Slide 77, shown in FIG. 6a, has its slide cover removed and shows a portion of the cover plate 90 broken away to expose the shoulders 77d and 77e in the slide. However, the cover plate 96 and fastening means 97 are shown in FIG. 6a for slide 89. Each of the cutters are provided with a sharp forward edge arranged to pass through associated slots 74c, and 74d and 74e provided in mandrel 74. In operation, the electron gun structure is placed upon the mandrel 74 which is provided with two projections 98 and 99 that are arranged to fit in the openings 100 and 101 shown in FIG. 3b which are defined by the ring sections and the supports to which they are welded. This establishes orientation between the cutter blades and the electron gun structure. Initially, the connecting rod 81 is in its uppermost position (not shown) relative to FIG. 6a. Air pressure is introduced to move the connecting rod 81 vertically downward relative to FIG. 6a to thereby move the cam ring 50 78 in the counterclockwise direction. The cam followers 82-84 move inward along respective radii of the cutter to form the gaps 40, 41 and 42, shown best in FIG. 3b. The air cylinder 79 is then operated to move the connecting rod 81 vertically upward relative to FIG. 6a causing the cam ring 78 to rotate in the clockwise direction and thereby remove the slides and their associated cutters outwardly along their respective radii. The electron gun structure may then be removed and transferred to the next location whereupon the heater filaments may be inserted within 60 the cathode openings and these filament leads such as the filament leads 28 may then be welded or otherwise electrically connected to the associated ring section such as, for example, sections 29 and 30, to establish a series electrical circuit to connect a power supply through tabs 12 and 13 to each of the three filaments of the electron guns comprising the structure.

It can be seen from the foregoing description that the present invention provides an automated means for simply and rapidly forming a cathode heater ring assembly and electron gun structures in which the number of fabrication steps are significantly reduced as compared with conventional techniques through the use of a single stamped member which is formed in an arcuate manner upon a fixture positioned relative to the electron gun structure welded at a plurality of locations and then cut

into a single cutting operation to form the cathode heater ring assembly.

Although there has been described a preferred embodiment of this novel invention, many variations and modifications will now be apparent to those skilled in the art. Therefore, this invention is to be limited, not by the specific disclosure herein, but only by the appending claims.

What is claimed is:

1. A method for forming a ring shaped structure comprised of separate sections welded to associated supports provided in a support structure comprising the steps of:

- (a) providing a flat C-shaped metallic member;
- (b) positioning said member about a circular shaped fixture to impart a circular configuration to said member;
- (c) releasably securing the arms of said member to said circular shaped fixture to cause said member to retain its circular configuration;
- (d) fitting said structure upon said fixture with said supports engaging said member at points along its outer surface;
- (e) welding said supports to said member at each of said points;

5

10

15

20

- (f) removing said structure and said member from said fixture;
- (g) cutting said member at predetermined locations to form said separate sections.

2. The method of claim 1 wherein step (g) is further comprised of simultaneously forming all of said cuts.

3. The method of claim 1 wherein step (e) is further comprised of the steps of removably mounting said fixture upon a rotatable structure; rotating said fixture to sequentially index each of said points for the welding operation.
